UNITED STATES PATENT OFFICE

SAMUEL I. BERGER, OF NEWARK, NEW JERSEY

TOY TRACTOR

Application filed July 8, 1929. Serial No. 376,793.

My present invention relates to toys, and more particularly it pertains to toys of the self-propelled type.

The invention is shown embodied in a toy tractor characterized by its ability to climb steep grades, and negotiate unassisted, obstructions and depressions in its pathway which would prove insurpassable obstacles to an ordinary self-propelled toy of similar size. Another characteristic of the invention resides in the marked similarity of its manœuvres, when in operation, to those of the full sized vehicle which it simulates.

An object of the invention is to provide a rugged toy of the afore-mentioned character in which a relatively powerful spring motor applies a slow motion and a powerful torque to the driving mechanism of the traction elements, and in which the traction elements are peculiarly well suited for insuring maximum traction on smooth surfaces as well as on rough and uneven ones.

Another object is to so construct a toy of this character as to enable it to assume apparently precarious angles both fore and aft and laterally without danger of toppling over.

Another object is to embody the chassis and power plant in a unitary structure of substantially standard design so constructed and arranged that bodies in imitation of various types and designs of vehicles may be readily applied thereto without change in the construction thereof.

Another object is to provide a toy not only realistic in appearance but strangely realistic in action and which with its slow motion and powerful traction captivates the observer with its symbolic portrayal of limitless power and disregard for obstacles. This effect is enhanced by the sturdy appearance of the toy and its unusual smoothness in action.

The invention will be more fully understood from the following description in con-

nnection with the accompanying drawings illustrating one of various possible embodiments of the several features of the invention, and wherein:

Fig. 1 is a perspective view of a toy tractor constructed in accordance with the present invention, 50

Fig. 2 is a vertical longitudinal sectional view thereof,

Fig. 3 is a transverse vertical sectional view taken on the line 3—3 of Fig. 2, 55

Fig. 4 is a vertical transverse sectional view taken on the line 4—4 of Fig. 2, and

Fig. 5 is a perspective view of the toy in partially disassembled relation. 60

The toy preferably comprises two separate units, one a chassis and power plant and the other a body which may be formed in imitation of any type of motor vehicle, and which is removably associated with the chassis. In Fig. 5 these two elements are designated by the reference characters A and B, respectively. 65

The body B preferably comprises a thin-gauge, open-bottomed shell-like member 10 adapted to be cheaply pressed or stamped into the desired shape which is adapted to fit over the heavy gauge chassis A and completely enclose the same. The chassis is of cheaper sturdier material and may be of standard size and shape substantially fitting reinforcing bodies of any design. The body is provided with spaced tongues or the like 11 extending downward from its lower edge and adapted for reception in similarly spaced openings 12 in a plate 13 which coacts with the chassis to enclose the motor mechanism. The tongues are bent over as best shown in Fig. 1 securely to retain the body and chassis in assembled relation. The body B may be 75

provided with an imitation steering wheel 14 protruding from its upper wall; it may have exhaust pipes 10a embossed thereon, and may be otherwise suitably ornamented to simulate the full sized vehicle. 80

The chassis element is preferably formed from a single sheet of metal suitably shaped to form a top 16 and side walls 17. Mounted in the side walls 17 of the chassis element are front and rear axles 18 and 19. These axles are mounted in suitable bearings 20 and carry front and rear wheels 21 and 22, respectively, preferably of the disc type formed to present channelled peripheries at 25.

- 10 Channels 25 in the present illustration of the invention are V-shaped in cross section and receive resilient traction elements preferably in the form of traction belts 26. As more clearly shown in Fig. 3, these traction belts, throughout that portion of their cross-sectional dimension designated 27 are shaped to conform to the peripheral grooves 25 of the wheels and are preferably placed around said wheels under a slight tension. The traction belts 26 are preferably formed from relatively soft rubber and they are preferably thicker than the depth of the channels 25 to project beyond the periphery of the wheels in their passage therearound as indicated at 28 in Fig. 3. The surface engaging face of the traction belts is formed with a plurality of recesses or depressions 30, defining webs 31 between, which extend transversely of the direction of travel of the traction belts.
- 15 20 25 30 35 40 45 50 55 60 65 70 75 80 85 90 95 100 105 110 115 120 125 130
- 28 These traction belts 26 form the means for supporting the toy upon the surface over which it travels and they also furnish the necessary traction for propulsion of the toy over smooth surfaces or obstacles placed in its path as well as up relatively steep grades. The rectangular cells between the side walls of the belt 26 and each of the adjacent webs 31 will under suitable conditions, perform a suction cup action.
- 30 35 40 45 50 55 60 65 70 75 80 85 90 95 100 105 110 115 120 125 130
- 40 The front driving wheels 21 are fixed with relation to their respective axle 18 which is driven by means of a suitable motor preferably of the convolute spring type.

- 45 To accomplish the driving of the axle a gear 32 is fixed thereto. This gear 32 meshes with the main driving or master gear 33 held by a ratchet plate 80 in one-way driving connection with the main shaft 34 of the motor. Ratchet plate 80 keyed on the motor shaft is urged by spring 81 against the face of gear 33, free on the motor shaft. Tongues 82 in the ratchet plate engage in slots 83 in the gear 33 positively driving this gear as the motor spring unwinds but as the motor spring is wound with the gear train of which 33 forms a part held against rotation, the ratchet plate slips relatively to gear 33. One end of shaft 34 is extended as at 35 and bent to provide a winding key 36. The shaft 34 is preferably journalled in the side walls 17 of the chassis element and anchors the inner end of a convolute spring 37, the opposite end 28 of which may be anchored as at 39 to the forward portion of the upper wall of chassis element A.
- 50 55 60 65 70 75 80 85 90 95 100 105 110 115 120 125 130
- 65 To insure proper alinement of the several

convolutions of the spring 37 suitable channel plates 38 may be soldered at their upper ends to the top wall of the chassis element A and preferably serve as axial supports for the arbor 34.

70 A speed multiplication gear train actuated from motor shaft 34 terminates in a suitable centrifugal governor which controls the delivery of energy for the slow speed high torque propulsion of the vehicle.

75 The governor comprises a yoke member 40 carried by a governor shaft 41 and soldered or otherwise affixed thereto to rotate therewith. A pair of levers 42 preferably of sheet metal are each fulcrumed intermediate their ends between pairs of ears 43 projecting from opposite sides of the yoke member 40. The longer arms of the levers 42 are provided with suitable centrifugal weights 45. These weights are formed by reversely bending the relatively wide flat free ends of the levers. Flat springs 46 normally retain said levers in parallelism and are clamped at their free ends between the folded ends of the levers. The other ends of the springs are retained as shown between the yoke and the lever fulcrums and confined against lateral movement by ears 43.

80 85 90 95 100 105 110 115 120 125 130

85 The outward movement of the centrifugal weights causes the inner ends of the levers which are curved at 44 to fractionally engage the face of the adjacent side wall 17 of the chassis element. This friction while light will be sufficient to exert the desired retarding effect upon spring 37 of the motor since the torque of the high speed governor shaft is negligible. The arms 42 are swung about their pivotal point by centrifugal force against the action of springs 46 which springs as governor shaft speeds decrease also serve to move the arms 42 into parallelism with the shaft 41 and in so doing move the curved ends 44 of said arms 42 out of engagement with the adjacent face of the side wall of the chassis element in which position they are shown in Fig. 4.

100 105 110 115 120 125 130

95 The train of speed multiplying gears to governor D is mounted in a suitable frame F, preferably in the form of a plate 50 spaced from the adjacent side wall of the chassis element and by which it may be carried. This train E of gearing preferably comprises shafts 41, 52 and 53 the ends of which are preferably mounted in the opposite side walls 17 of the chassis element. The shaft 41 has rigidly attached thereto a pinion 54 which is driven to rotate said shaft 41 by means of a large gear 55 mounted upon the shaft 52. A pinion 56 is preferably fixedly attached to the gear 55, and meshes with a large gear 57 on the shaft 53. A pinion 58 preferably is fixed to the large gear 57 and this pinion meshes with the master gear 33.

110 115 120 125 130

120 From the foregoing, it will be obvious that as the spring 37 is permitted to expend the

energy previously stored therein by placing said spring under tension, the front axle 18 will be driven from the master gear 33 through the medium of the gear 32 with which 5 the master gear 33 meshes. The speed at which the front axle is driven is determined by the retarding effect of the governor D due to the friction between the curved ends 44 of the arms 42 and the adjacent face of the 10 side wall of the chassis element. To prevent release of the motor spring during winding a lever 61 is pivotally mounted intermediate its ends on the inner face of the chassis side frame 17, as at 62. The inner end 60 of the 15 lever is movable to block rotation of the governor D by swinging the handle end of the lever (which extends up through slot 60a in the chassis) and consequently the gear trains are held against turning and the spring 20 against unwinding as the winding key is turned. However, the ratchet plate 80 slips relatively to the gear 33 as above described to permit winding of the spring without imparting motion to the toy.

25 Lever 60 may be swung at any time to stop the toy while in motion. As the spring becomes unwound to the desired extent its outer convolution strikes the governor and thereby locks the gear trains and prevents further unwinding.

In addition to controlling the speed at which the toy is driven, the governor controls automatically the degree of power transmitted by the motor to the traction elements 35 and this phase of the governor operation will now be explained.

Assume that the toy is moving along a relatively smooth surface and in so doing meets an obstruction which it must surmount. The 40 obstruction offers resistance to the forward movement of the toy and as a consequence the governor D is slowed down which reduces or entirely removes the friction at the point 45 of contact of the curved ends of the arms 42 with the adjacent side wall of the chassis element. The reduction or elimination of the friction at this point by reason of the slow rate of speed of rotation of the governor 50 D permits the spring 37 to exert its full force directly upon the front axle 18 from which it is transmitted to the traction belts 26 and causes the toy to move over the obstacle. Upon passing clear of the obstacle, and upon 55 a relatively level surface again, the motor speeds up the governor until the curved ends 44 of the arms 42 engage the adjacent side wall of the chassis element and thus produce sufficient friction to cause the motor to operate 60 again at the desired slow speed.

To give a realistic appearance to the toy, a suitable figure 70 in imitation of an operator may be employed. This figure is preferably retained in position upon a seat 15 65 by means of a spring tongue 71 carried by

the figure 70 and adapted to be received in an opening 72 in the seat 15.

From the foregoing it will be apparent that the present invention provides a novel toy which is unique in appearance and operation, 70 is sturdy in construction and which can be manufactured at a relatively low cost.

75 While the invention has been herein illustrated in its preferred form, it is to be understood that it is not limited to the form in which it is illustrated and that it may be carried out in such other forms as rightfully fall within the purview of the appended claims.

Having thus described my invention, what 80 I claim as new and desire to secure by Letters Patent is:—

1. In a toy of the self-propelled type, a chassis and power plant assembly of substantially standard construction, and a body-simulating member in the form of a shell adapted to substantially fit over, snugly embrace, and conceal said chassis member. 85

2. In a toy of the self-propelled type, a chassis and power plant assembly of substantially standard construction, and heavy gauge material, a body-simulating member in the form of a light gauge shell adapted to snugly fit, enclose and be internally reinforced by 90 said chassis member, and means for securing 95 said chassis element and said body-simulating shell together.

3. In a toy of the self-propelled type, a chassis and power plant assembly of substantially standard construction, a body-simulating member in the form of a shell adapted to receive therein said chassis member for fitted union, and means for securing said chassis element and said body-simulating shell together, said means including a plate constructed and arranged to close the body-simulating member about the chassis element. 100 105

4. In a toy of the self-propelled type, a chassis and power plant assembly comprising a sheet metal body member of substantially inverted U-shaped cross-sectional form, a body-simulating shell member adapted to receive and snugly fit said chassis element, and a plate adapted for attachment to said shell 110 member to secure the chassis element therein 115 and close the bottom of the chassis.

5. In a toy of the self-propelled type, a chassis and power plant assembly comprising a sheet metal body member of substantially inverted U-shaped cross-sectional form, a motor mounted interiorly of said chassis element, a body-simulating shell member adapted to receive and snugly fit said chassis element, and a plate adapted for attachment to said shell member to secure the chassis element therein, and to enclose the motor in said chassis element. 120

6. A toy of the self-propelled type including a chassis element, traction means therefor, and a motor for driving said traction 130

means, said motor including a main driving shaft extending transversely of the chassis element, and a convolute spring carried by said transversely extending shaft, and positioned in a plane at right angles to the axis thereof, and means depending from the top of the chassis element and flanking said spring on both sides to prevent distortion thereof.

10 Signed at Newark, in the county of Essex and State of New Jersey this 5th day of July A. D. 1929.
